UNITED STATES PATENT OFFICE.

OLOF L. BROLINE AND JOHN A. NOLAN, OF CHICAGO, ILLINOIS.

ROLLER-SCREEN.

1,259,480.

Specification of Letters Patent. Patented Mar. 19, 1918.

Application filed August 31, 1916. Serial No. 117,960.

To all whom it may concern:

Be it known that we, OLOF L. BROLINE and JOHN A. NOLAN, citizens of the United States, and residents of the city of Chicago, 5 county of Cook, and State of Illinois, have invented certain new and useful Improvements in Roller-Screens, of which the following is a specification.

Our invention relates to improvements in 10 roller window screens designed for use particularly in connection with casement windows that is windows of the type in which the sashes are swingingly or hingedly mounted. With windows of this type it is impractical to use the ordinary form of window screen for the reason that the sashes are mounted to swing outwardly and, this being the case, where screens of the ordinary type are used, the same interfere with the outward swinging of the sash. It is impossible to use the screens at the inner side of the window for the reason that the same cannot be slidably mounted and it is inconvenient and awkward to require the screen to be 20 moved in order to gain access to the window sash.

The object of our invention, therefore, is 30 the production of a roller screen adapted to effectually screen a window of the casement type and which will afford ready access to the window sash. A further object is the production of improved means for locking the lateral edges of the flexible screen employed to the sides of the window frame.

35 Other objects will appear hereinafter.

The invention consists in the combinations and arrangements of parts hereinafter described and claimed.

The invention will be best understood by 40 reference to the accompanying drawings forming a part of this specification, and in which,

Figure 1 is a partially sectional front elevation of a casement window to which is applied a screen embodying the invention,

Fig. 2, a vertical transverse section of Fig. 1,

Fig. 3, a horizontal section through one side of the window frame,

Fig. 4, an elongated section through one edge of the screen, and

Fig. 5, a vertical transverse section similar to Fig. 2, showing a slightly modified form of construction.

55 The preferred form of construction as illustrated in the drawings is shown in con-

nnection with a casement window sash 7 which is swingingly mounted upon hinges 8 in the window frame 9.

Arranged in the upper end of the window frame 9 is a sheet metal housing or casing 10 in which is mounted a spring roller 11 of the type now generally in use in connection with window shades. Coöperating with the roller 11 is a flexible screen 12 the upper 60 end of which is fixed to said roller, said screen being adapted to be wound upon said roller as clearly illustrated in Figs. 1, 2 and 5.

The outer end of screen 12 projects downwardly through an opening 13 at the underside of housing 10, the lower end of said screen being fixed to a cross bar 14 which is longitudinally recessed at its upper edge for the reception of said end of said screen. 75 Suitable fastening devices are employed for fastening said screen and cross bar together.

The lateral edges of the screen 12 slidably engage in guide grooves 15 each of which is formed by two spaced longitudinally extending strips 16 and 17 which are secured at each side of the window frame as seen in the several views.

To prevent displacement of the lateral edges of the screen from said grooves such 85 as might result when pressure is applied to the screen, said screen edges are provided with a plurality of spaced enlargements 18. The grooves 15 are enlarged at their inner ends to accommodate the enlargements 18, 90 the latter being of a width or thickness greater than the outer reduced portions of said grooves as clearly seen in Fig. 3. Each of said enlargements, as seen in Figs. 3 and 4 comprises two semi-cylindrical blocks 18' 95 and 18'' which are rigidly secured to the screen, which is arranged between the same, by means of a screw 19. The cylindrical formation of said enlargements is of particular advantage in that the rounded sides 100 thereof develop the least friction in the sliding of the same in the grooves 15, and the construction is such as to permit of ready and expeditious application to the edges of the screen. To alleviate wear upon the strips 16 and 17, the edges thereof at the grooves 15 are lined with sheet metal lining strips 20.

In order to guide the cross bar 14 in the vertical movement of the screen, the respective ends of said bar are equipped with sheet metal end pieces 21 each of which is formed

with a reduced outer end portion 22 which slidably engages in the corresponding groove 15 as seen in Fig. 3.

In use the enlargements will be spaced 5 upon the lateral edges of the screen at comparatively wide distances, it being necessary to employ but few in order to properly hold the edges of the screen against displacement. By employing but a few of said enlargements, the same will not interfere materially with the screen in the winding of the same about the roller 11 as would otherwise be the case were a large number of said enlargements employed.

15 In order to lock the screen in lowered or operative position, the lower edge of the cross bar 14 is provided with a suitable lock 24 adapted for releasable engagement in a socket 25 provided upon the stool or inner 20 sill of the window.

Where the device is installed in an old window frame, that is a window frame of the type now generally in use, the construction disclosed in Figs. 1 and 2 would be employed. Where the screen is installed in a new construction, the housing 10 will be dispensed with and the roller 11 arranged above the window opening that is in the hollow upper bar of the window frame as seen in 25 Fig. 5. An opening 13' will be provided for the passage of the screen. If desired the strips 16 and 17 may be so arranged in the window frame as to serve the additional function of stops for the window sash as 30 seen in Fig. 3.

While we have illustrated and described the preferred form of construction for carrying our invention into effect, this is capable of variation and modification without 40 departing from the spirit of the invention. We, therefore, do not wish to be limited to the precise details of construction set forth, but desire to avail ourselves of such variations and modifications as come within the 45 scope of the appended claims.

Having described our invention what we claim as new and desire to secure by Letters Patent is:

1. The combination with a window frame 50 and a sash mounted therein, of a roller

mounted in said frame adjacent said sash; a flexible screen connected with said roller and adapted to be wound thereon; guide grooves at the sides of said frame slidably engaged by the lateral edges of said screen, 55 said grooves being enlarged at their inner ends; and enlargements spaced along said edges of said screen engaging in said enlarged portions of said grooves, said enlargements being cylindrically formed with 60 their axes extending transversely of the screen, substantially as described.

2. The combination with a window frame and a sash mounted therein, of a roller mounted in said frame adjacent said sash; 65 a flexible screen connected with said roller and adapted to be wound thereon; guide grooves at the sides of said frame slidably engaged by the lateral edges of said screen, said grooves being enlarged at their inner 70 ends; and enlargements spaced along said edges of said screen engaging in said enlarged portions of said grooves, said enlargements being cylindrically formed with their axes extending transversely of the screen, 75 each of said enlargements being formed of two semi-cylindrical parts rigidly secured together with the screen arranged between the same, substantially as described.

3. The combination with a window frame 80 and a sash mounted therein, of a roller mounted in said frame adjacent said sash; a flexible screen connected with said roller and adapted to be wound thereon; guide grooves at the sides of said frame slidably 85 engaged by the lateral edges of said screen, said grooves being enlarged at their inner ends; enlargements spaced along said edges of said screen engaging in said enlarged portions of said grooves, said enlargements being cylindrically formed with their axes extending transversely of the screen, each of 90 said enlargements being formed of two semi-cylindrical parts arranged at opposite sides of the screen; and a fastening screw passing through the screen and connecting said parts, the ends of said screw being countersunk in said parts, substantially as described. 95

OLOF L. BROLINE.
JOHN A. NOLAN.
